US00D646677S

(12) **United States Design Patent**
Moon et al.

(10) **Patent No.:** **US D646,677 S**
(45) **Date of Patent:** **** Oct. 11, 2011**

(54) **NOTEBOOK COMPUTER**

(75) Inventors: **Ji-Hyun Moon**, Kyunggi-do (KR); **Dae-Joung Kim**, Seoul (KR); **Jin-Le Ryu**, Seoul (KR); **Chul-Yong Cho**, Seoul (KR)

(73) Assignee: **Samsung Electroncis Co., Ltd.**, Suwon, Kyunggi-Do (KR)

(**) Term: **14 Years**

(21) Appl. No.: **29/372,114**

(22) Filed: **Oct. 15, 2010**

(51) **LOC (9) CL. 14-02**

(52) **U.S. Cl. D14/315**

(58) **Field of Classification Search** .... D14/315-327; D18/1, 2, 7, 11; 235/145 A, 145 R; 341/22, 341/23; 345/156, 157, 168, 169, 173; 361/679.27, 361/679.09; 348/373; 715/783

See application file for complete search history.

Primary Examiner — Freda Nunn

(74) *Attorney, Agent, or Firm* — Flynn, Thiel, Boutell & Tanis, P.C.

(57) **CLAIM**

The ornamental design for a notebook computer, as shown and described.

DESCRIPTION

FIG. 1 is a top front perspective view of a notebook computer showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

1 Claim, 4 Drawing Sheets
